DESIGN FOR A FOLDING KNEE MIRROR

Paul M. MacWilliams, Burbank, Calif., assignor
to Louis M. Neubeiser and Wanda E. Neubeiser,
both of Glendale, Calif.

Application February 21, 1948, Serial No. 144,664

Term of patent 14 years

(Cl. D86—2)

To all whom it may concern:

Be it known that I, Paul M. MacWilliams, a citizen of the United States, residing at Burbank, in the county of Los Angeles and State of California, have invented a new, original, and ornamental Design for Folding Knee Mirror, of which the following is a specification, reference being had to the accompanying drawing, forming part thereof.

Fig. 1 is a perspective view of a folding knee mirror, showing my new design, in position to set on a flat surface.

Fig. 2 is a perspective view with the mirror in another position for placement on the knee of the user.

Fig. 3 is a plan view of the mirror folded flat.
I claim:

The ornamental design for a folding knee mirror, substantially as shown and described.

PAUL M. MACWILLIAMS.
